2 Claims. (Cl. 219—11)

1

This case concerns an invention in a mechanism for heating or drying continuous or substantially continuous lengths of current conducting material. More specifically, the invention involves a mechanism for heating or drying cable.

According to previous practice, cable has been dried by conducting it through a heating chamber and blowing a current of air through the chamber and about the cable, but that practice is generally unsatisfactory in that the inner part of the cable is not dried, or if sufficient time is taken to dry that part of the cable the progress of the cable through the drier must be extremely slow. The method and mechanism herein described are adapted to dry a cable or other conducting type material while the same is being progressed rather rapidly and by suitably regulating the process in a manner hereinafter described, all parts of the cable will be dried without excessively heating the outside of the cable and without prolonging the period of time it is subjected to the drying action merely for the purpose of accomplishing drying at the inner strands or core.

While any type of cable or other conducting material may be dried by the mechanism involved, the invention is described with respect to drying cable after it has been plated or tinned whereupon it is generally washed at some point in the process. The cable may then be covered with insulating material or may have rubber bonded thereto. Such bonding with rubber is practiced in the manufacture of treads for track type vehicles in which steel cables are first plated and thereafter imbedded in the rubber tread of the track which is actually bonded to the metal of the cable. The washing occurs at some point after one of the plating operations and since the material must be clean before proper bonding can be realized, the washing is done just before the cable and rubber are bonded and thus thorough drying during progress of the cable in the continuous process is essential. The cable must be dried without excessively heating the same since it is quite possible that some effect on the plating might be experienced if that were done.

While only one section of a complete machine adapted to dry cable according to the present invention is described here, it is to be understood that the machine may be constructed so as to have as many sections as desired and therefore to act upon many cables simultaneously. One of the objects in the development of this type of drying means has been that of rendering the mechanism safe, and, to that end, a low voltage, 55

high amperage current is employed. The external wiring is as short as possible to eliminate losses, thereby making the process economical. Each individual cable is drawn through the machine by an independently driven traction means which preferably comprises an electric motor geared to a take-up and controlled as usual to maintain the cable taut and wind it on a drum. Each of these units has a zero-speed switch which functions to control the drying current flowing in the cable so that whenever it is stopped, that current will be shut off until the cable is again started through the machine. Actually, this zero-speed control operates to turn on the drying current after the driving motor has picked up a pre-determined number of revolutions per minute; also shuts off the current when that motor speed drops below a pre-determined number of revolutions per minute.

20 The drying current is brought to the machine through a variable resistance and is transformed by any convenient type of transformer, for example, an iron core type transformer having its secondary side connected to the cable or other material to be dried, which material is so guided and the wiring connections thereto so designed that the drying current is confined to a predetermined portion or zone in the advancing cable. This secondary side of the transformer is at relatively low voltage, for example, 6 to 14 volts. There are a plurality of taps at the secondary side of the transformer and by employing different ones of these, the voltage and current characteristics used for drying may be varied.

25 The cable is guided over trolleys, two of which are fixed at the top of the machine frame while the other is adjustably supported, one purpose thereof being to vary the length of cable in which the drying current is allowed to flow. This movable trolley is the means through which current is initially introduced to the cable and forms a sort of dividing point in that part or length of the cable being dried. One portion of that part or length is shorter than the opposite whereby a greater flow of current is permitted in the short side than in the longer side. Incidentally, the shorter side is that in which the initial drying is accomplished whereas the second part of the cable to be dried and which has a lower rate of current flow constitutes the second stage of drying, however, for other purposes the opposite arrangement may be more desirable. The relative lengths of these two stages as well as the total length of cable in the drying zone 45 may be varied.

A system of bus bars is employed by means of which the fixed trolleys are interconnected and through which current flow is completed back to the secondary side of the transformer. These fixed trolleys are also grounded to the frame. This system of wiring serves to offer as little electrical resistance as possible so that power loss is kept at a minimum. Drying of the cable due to heat rise caused by resistance therein is thus accomplished with a minimum of electric power consumption.

By dividing the current flow between two portions of the current carrying part of the advancing cable and by having the initial portion of that cable shorter than the second part in which current is flowing, the temperature of the cable is raised very quickly as it enters the heating zone. However, the outside or surface portion of the cable is heated much more quickly than the center or core. To heat the entire cable rapidly, the current necessary could not be maintained for long as it would very likely increase the temperature above safe limits. To eliminate any unevenness in heating, the first heating stage or zone is followed by another during which less but sufficient current flows to maintain desired temperature and permit uniform distribution of heat and drying effect throughout the cable. The outside part of the cable is actually dried during this initial stage or first zone of its travel through the machine. In the second zone the reduced flow of current and greater resistance is only sufficient to maintain temperature, that is, the temperature at the outside of the cable is not raised substantially beyond that point to which it was raised in the initial zone. However, due to the fact that travel through this second zone is longer than the first and since the outside of the cable is substantially dry and at its maximum temperature, the center or core of the cable will be dried in that time, being affected by both the resistance to the flow of current and also by conduction of heat from the outside inwardly to the core.

The invention will be further described by reference to one specific embodiment of the same as illustrated in the accompanying figures of drawings in which:

Fig. 1 is a plan view of a section of the drying machine, this section being adapted to accommodate two separate cables;

Fig. 2 is an end elevation of the machine showing means for guiding the cable, one of the transformers and wiring and the zero-speed switches;

Fig. 3 is an elevation at the back of the machine showing zero-speed switches;

Fig. 4 is a detail of one of the trolleys for guiding cable through the machine and by means of which current is conducted to or from the cable;

Fig. 5 is a section showing the zero-speed switches and drive for the same; and

Fig. 6 is a diagrammatic view illustrating in a more or less elementary way the wiring incidental to drying a single cable.

Now referring to Figs. 1, 2 and 3, the machine is built up on a frame work structure which includes posts 19 and 11 and cross members 12 and 13, also longitudinal members 14 and 15 at the top and 16 at the bottom. There is another longitudinal member at the opposite side from the member 16 although that does not show in any of the figures. It is to be understood that the frame work may be as long as desired or as is necessary for accommodating the particular num-

ber of cables or other current carrying elements which are to be progressed through the machine. For each cable, one of which is indicated by a dot-and-dash line 17, there is a trolley 18 at what will be termed the front of the machine, an adjustable trolley 19 and then another trolley 20 at the back side of the machine, these trolleys preferably being identical in construction. The trolleys 18 and 20 are fixed in position at the top of the machine and serve as guiding means for the cable, also are grounded to the frame by means of wires 21 and 22.

The trolley 19 is rendered bodily movable to and from the trolleys 18 and 20 since it is mounted to be moved vertically along the post 11. This trolley which is rotatable within a harp 23 is fixed to an insulating board 24 made of Transite or other material suitable for the purpose, and this insulating board is attached to brackets 25 and 26 which clamp to the post 11 and thus may be locked in any desired position on that post. In actual practice the board 24 extends the entire length of the frame and a plurality of brackets 25 and 26 will be unclamped from their respective posts 11 in the event the trolleys 19 are to be adjusted, the entire assembly will be moved to a desired position and then all will be clamped by tightening the clamping means, the same not being illustrated in detail in this case. Dotted line positions indicate more or less the extremes to which the movable trolleys may be adjusted for a purpose hereinafter more definitely to be described.

Referring to Fig. 4, one of the trolleys such as 19 is illustrated being freely rotatable upon an axle 27 passing through the harp 23, that harp being bolted or otherwise suitably attached to the board 24 in the event the unit is to be insulated from the frame, but in the case of trolleys such as 18 and 20, being attached to any suitable bracket welded or otherwise fixed at the top portion of the frame structure. Current connection to the trolleys is by a wire soldered to a contact clip 28 which is slipped over the axle 27 as the unit is assembled and which is pressed against the end of the hub of the trolley by a contact spring 29. The cable 17 is guided within a small groove 30 within a larger groove with which the trolley has originally been provided. Depending upon the size of cable to be handled and other factors, the diameter and general characteristics of these trolleys may vary. Generally speaking, they are similar to trolleys used for taking current from trolley wires as in street cars or other railway equipment.

At the back of the machine two angle irons 31 and 32 extend the length of the frame work and carry supports for the zero-speed switches. Each switch is driven by the moving cable as the same passes about a sheave 33 grooved to receive it. As shown more clearly in Fig. 5, a grooved sheave 33 is keyed to one end of a shaft 34 rotatable on ball bearings 35 and 36 in the bearing closures 37 and 38. These closures are bolted to a horizontally disposed shelf 39 extending outwardly from vertical supports 40 and 41 which are welded or otherwise attached to the angle irons. Each switch 42 is bolted to the lower side of the horizontal shelf 39 and is driven by the rotation of shaft 34 under influence of the moving cable and through gearing including pinion 43 and gear 44. The pinion 43 is pinned to the end of the motor shaft and gear 44 is keyed to shaft 34.

The zero-speed switches function to control the heating or drying current so that when the cable

stops or slows down to a point where the switch rotates at about 30-40 R. P. M. the current is shut off. Alternatively, as speed builds up, the current is again caused to flow as the zero-speed switch rotor reaches about 50 R. P. M. Of course, these speeds are adjustable as desired. This prevents overheating the cable and also makes it impossible to draw cable through the machine when drying current is not flowing, that being something which would lead to difficulties since undried cable might then be subjected to a bonding step, and, of course, the wet cable would not be properly bonded to the rubber.

A series of bus bars 45 are connected across between the frame members 14 and 15, while bus bar 46 extends lengthwise of the frame and connects to each one of the transverse bars 45. The trolleys 18 and 20 are actually grounded to the frame through these bus bars by connection of the short cables 21 and 22. The bus bars are not insulated from the frame, but attach directly thereto.

The secondary side of the transformer is connected by means of a conductor 47 to the trolley 19, that conductor being soldered to a clip such as the clip 28, Fig. 4, so that the current is carried through the trolley wheel and then to the cable to be dried since that cable is in contact with the wheel. The current divides at that particular point part flowing through the cable extending from the trolley 18 to trolley 19, the other part going to that length of the cable which passes from trolley 19 up to and over trolley 20.

The amount of current passing through these portions of cable of unequal length varies inversely as the resistances therein. By moving the trolley 19 as before described it is possible to lengthen or shorten the entire amount of cable in which current flows and also to vary the relative length of the two parts of the cable. A second conductor 48 attaches to the bus bar 46 and that completes the circuit back to the transformer. The bus bars 45 and 46 are of copper and are designed to set up a minimum of resistance so that practically all the current being used is employed to overcome resistance in the cable itself and therefore for heating purposes. The grounding of the trolleys 18 and 20 to the frame also decreases the resistance in the entire system thereby making it possible to use very little current and especially, to obtain heating effect in the cable from as great a proportion of the current as possible. The secondary side of the transformer is also grounded to the machine frame.

In actual operation of the drier the resistance in that part of the cable moving between trolley 18 and trolley 19 is less than in that part between trolleys 19 and 20. The resistance in the first part is considerably less than in the second part and with the voltage and amperage of the current available allows that first length of cable to become heated very quickly. However, that cable is heated at the surface, or strands close to the surface are heated first, while those at the core are not heated to the same extent so that the outside of the cable tends to be dried much more rapidly.

To compensate for that effect, the length of cable moving in the second part of the pathway, that is, between trolleys 19 and 20, offers considerably more resistance and allows less current to flow so that rather than having its temperature raised to a still greater height, that cable is maintained at substantially the temperature in-

duced in it during its travel in the first pathway. However, since the pathway is longer and while the outside of the cable remains at substantially constant temperature, the inside will be brought to that same temperature by conduction of the heat from the outside toward the inside with accompanying drying at the inside. For different conditions such as variations in size, material from which the cable is made and other factors, the pathway through which it passes for drying may be lengthened or otherwise altered so as to accomplish the drying at as great a speed as possible, yet assuring that the cable will be completely dried outside and also at the core.

Of course, the cable or other material to be dried is continuously being advanced or drawn through the machine so that the description here of what is happening to the cable in the first or second stages or zones of drying may be considered as applying to an incremental length of cable as it passes through those zones.

Now referring to Fig. 6, the cable 17 is shown passing over trolley 18, around under trolley 19 and then over the third trolley 20. The trolleys 18 and 20 are connected by the bus bar 45 and each of the trolleys is grounded as at 49. An iron core type transformer 50 has a primary winding 51, current being supplied to that primary winding through a variable resistance 52. The secondary side of the transformer comprises a secondary winding 53 and a series of taps 54, there being five shown here although that number may be varied according to requirements. The secondary side of the transformer is grounded at 55. Each of these taps allows current to be drawn from the secondary side of the transformer, said current being of differing voltages according to the particular tap used. For example, in one machine having a supply of current from a 440 volt-60 cycle-3 phase line, current may be transformed so as to make available for the drying process a current having from 6 to 14 volts and varying from 150 to 180 amperes. While 3-phase current is employed, each of the individual sections, that is, each transformer in a complete multi-section frame functions as a single phase circuit. The bus bar 46 runs lengthwise of the frame connecting to each transverse bus bar 45 and a conductor 48 is shown running from that bus bar 46 down to the return side of the secondary winding.

As actually constructed the wiring and controls for the entire unit pass through a rather elaborate switchboard and there are several safety devices, warning lights, etc., but those have not been illustrated here since they do not appear essential to a description of the invention itself. The drying of cable has been referred to by way of example, but it is to be understood that the invention is applicable to the drying of any material which may be heated due to its resistance to flow of current and which may be easily progressed through the machine at the desired speed. This method of drying and the mechanism are particularly adapted to use when the drying is performed in conjunction with other processes on the material and when it is desired that the drying be done continuously and in synchronism with these other processes.

Alternating current is preferably to be employed, but it is within the invention as originally conceived to employ direct current in the event alternating current is not available. The use of low voltage renders the entire mechanism comparatively safe and since control of the heat-

ing effect makes it unnecessary to resort to higher temperatures, the drying is carried on without any adverse effect upon the plating of the cable.

In some instances it may be desirable to divide the cable which is being dried into more than two zones or portions as herein illustrated. For example, there may be two or more movable trolleys such as the trolley 19 and thus the drying may be divided into more stages so that in the first temperature may be raised to a maximum very quickly, in the second stage drying may be carried through toward the center of the material and the last stage may be one in which temperature at the outside is maintained while the core is dried as heat is conducted through to the center and the entire cable or other material soaked in heat.

The invention may take varied forms and may be employed for many purposes other than those particularly referred to here without departing from the scope of the same as originally conceived and as expressed in the appended claims.

We claim:

1. Mechanism for drying a substantially continuous length of current conducting material while advancing said material at a uniform rate, including in combination, a frame comprising upright posts, top cross members and top and bottom longitudinal members, guide means for said material, said guide means comprising two fixed and one adjustable trolley, one of said fixed trolleys being mounted on the front portion and the other on the rear portion of said frame, said adjustable trolley being mounted intermediate the fixed trolleys relative to the path of travel of said current conducting material between said fixed trolleys, said adjustable trolley being insulated from said frame and being mounted upon a board which in turn is mounted upon brackets clamped to a said upright post by releasable clamps, said clamps when released being slidably

adjustable in a direction transversely to a straight line connecting said fixed trolleys and may be clamped in any selected position within the range over which the clamps are slidably adjustable on said upright post, a source of low voltage, high amperage current, consisting of a transformer mounted and grounded on said frame, a current connection from said source to the movable trolley consisting of a wire extending from said source to the axle of the movable trolley, said fixed trolleys being conductors and being grounded on said frame through which frame a circuit is completed back to said source.

2. Mechanism for drying a substantially continuous length of current conducting material while advancing said material at a uniform rate, including in combination, a frame guide means for said material, said guide means comprising two fixed and one adjustable trolley, one of said fixed trolleys being mounted on the front portion and the other on the rear portion of said frame, said adjustable trolley being mounted intermediate the fixed trolleys relative to the path of travel of said material being dried between said fixed trolleys, said adjustable trolley being insulated from said frame and being slidably adjustable in a direction transversely to a straight line between said fixed trolleys and may be clamped in any selected position within the range over which the clamps are slidable on the frame, a source of low voltage, high amperage current, including a transformer mounted and grounded on said frame, a current connection from said source to the movable trolley, said fixed trolleys being conductors and being grounded on said frame through which frame a circuit is completed back to said source from each of the said fixed trolleys.

GEORGE P. BOSOMWORTH.
